UNITED STATES PATENT OFFICE.

HENRY E. LEPPERT, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Application filed February 11, 1922. Serial No. 535,694.

To all whom it may concern:

Be it known that I, HENRY E. LEPPERT, a citizen of the United States of America, residing at New Britain, Hartford County, Connecticut, have invented a new and useful Electric Switch, of which the following is a specification.

My invention relates particularly to what are commonly termed snap switches or quick-break switches. Devices of this kind rely upon a spring to throw the switch contact when motion has been started by hand or finger operation. Sometimes the parts of such switches stick and they fail to act properly. In order to overcome this difficulty I provide a connection between the operating lever and the switch contact carrying arm, so that the switch arm is positively moved before time for the automatic spring action.

Figure 1 is a side view and partial section of one form of switch embodying the improvements of my invention;

Fig. 2 is a transverse sectional view of the switch mechanism proper;

Fig. 3 is a side view of the same on a somewhat larger scale, showing an extension of the operating lever;

Fig. 4 is a perspective view of the member which carries the removable switch contact; and

Fig. 5 is a perspective view of the operating member.

The switch proper has a frame 7 which is secured to a suitable insulating support 8, for instance, by means of one or more screws 9. A switch contact member is indicated by dotted lines at 10, though this invention does not relate to the particular form or arrangement of contacts. The movable contact member is suitably supported by an arm 11, which preferably has two semi-circular bosses 12, which are pivoted on the hub members 13 and may be pressed outwardly from the frame 7 as shown in my Patent No. 1,381,568.

The operating lever 14 or tilting plate has pivots 15, 15 at opposite sides, suitably supported in the sides of the frame 7. This

plate 14 also has one or more projecting lugs 16, adapted to swing in a slot or slots 17 in the frame 7, the ends of the slots serving as stops for the projecting lugs 16. One of the lugs 16 has a further projecting lug 18, which is adapted to engage the pins 19 and 20 of the switch arm 11 when the member 14 is tilted on its pivots 15, 15.

The spring 21 interposed between the bottom of the switch arm 11 and the inner end of the member 14 tends to hold the switch member against the lower part of the frame 7, as shown in Fig. 3, or the upper part of the frame, as shown in Fig. 1. Preferably the spring 21 is mounted on a rod 22, which is hooked onto one end of the member 14 and passes through a hole 23 in the switch member 11.

The tilting plate or lever 14 may be operated by means of a rocker 24 and push buttons 25, as shown in Fig. 1, or by means of a lever, which may have an insulating handle or finger piece, as indicated at 26 in Fig. 3.

When the lever is moved from the position shown in Fig. 3, the lug 18 engages the pin 20 and starts to move the switch member 11 just before the point of connection between the member 14 and the rod 22 passes the plane which contains the axes of the hubs 12 and the pivots 15. This starts a positive movement of the switch member before the spring begins to exert its snap action. Any tendency to stick and render the spring ineffective is thus eliminated.

I claim:

1. In a snap switch, a frame, a switch member and an operating member pivotally carried by said frame, said frame having a slot, said switch member having two projections and said operating member having a projection extending through said slot for engaging the projections of said switch member, and a quick-break connection between said operating member and said switch member.

2. In a snap switch, a frame, a switch member pivoted thereto, an operating lever, and a rod and spring connecting said lever

and said member, said member having two projections and said lever having a projection with a lost motion connection with the projections on said switch member.

5 3. In a snap switch, a frame, a switch member pivotally carried thereby, and an operating lever pivoted to said frame and

having a spring connection with said switch member, said frame having a slot and said operating lever having a lug projecting 10 through said slot for engagement with said switch member.

HENRY E. LEPPERT.
